Primary Examiner — T Chase Nelson*Assistant Examiner* — Rachel Wolfe(74) *Attorney, Agent, or Firm* — NIXON & VANDERHYE(57) **CLAIM**

The ornamental design for a light diffuser for lighting devices, as shown and described.

DESCRIPTION

FIG. 1 is a top perspective view of a light diffuser for lighting devices showing the new design;

FIG. 2 is a bottom perspective view thereof;

FIG. 3 is a top plan view thereof;

FIG. 4 is a bottom plan view thereof;

FIG. 5 is a side elevation view thereof;

FIG. 6 is a front elevation view thereof;

FIG. 7 is an opposite side elevation view thereof; and,

FIG. 8 is a rear elevation view thereof.

The broken lines shown in the drawings illustrate portions of the light diffuser for lighting devices that form no part of the claimed design.

1 Claim, 8 Drawing Sheets(56)
